DESIGN FOR A CUSHIONED SKIRT

Victor Silson, New York, N. Y.

Application September 26, 1941, Serial No. 103,514

Term of patent 7 years

To all whom it may concern:

Be it known that I, Victor Silson, a subject of the King of Great Britain, residing in New York city, county of New York and State of New York, have invented a new, original, and ornamental Design for a Cushioned Skirt, of which the following is a specification, reference being had to the accompanying drawing, forming part thereof.

Fig. 1 is a front view of a cushioned skirt showing my new design.

Fig. 2 is a rear view thereof.

Fig. 3 is a plan view of the reverse side of the cushioned skirt in open position illustrating the pillow portion.

Fig. 4 is a fragmentary view of the cushioned skirt as shown in Figure 3 showing the pillow portion inflated.

I claim:

The ornamental design for a cushioned skirt, substantially as shown.

VICTOR SILSON.
